Elmer H. Bard, P.O. Box 658,
Muskegon, Mich. 49443

Filed Jan. 6, 1969, Ser. No. 15,344

Term of patent 14 years

Int. Cl. D12—02

U.S. Cl. D14—3

The single figure in the drawing is a perspective view of a housekeeping cart embodying my invention.

The side opposite to that shown at the right is a mirror image thereof, with the exception of the intermediate tray having three sides and the end at the right is flat and plain.

I claim:

The ornamental design for housekeeping cart, as shown and described.
